UNITED STATES PATENT OFFICE.

GERARD J. TERWIEL, OF THE HAGUE, NETHERLANDS.

CAMERA.

1,326,470.

Specification of Letters Patent. Patented Dec. 30, 1919.

Application filed August 27, 1917. Serial No. 188,519.

To all whom it may concern:

Be it known that I, GERARD J. TERWIEL, subject of the Kingdom of the Netherlands, residing at the city of The Hague, Kingdom 5 of the Netherlands, have invented a new and useful Improvement in Cameras, of which the following is a specification.

This invention relates to improvements in cameras which employ a sensitized film carried by reels from which successive sections 10 may be unrolled and exposed, then rereeled and removed for developing in the usual manner.

One of the objects of the present invention 15 is to prevent double exposure of any section of the film. Another object is to provide means whereby successive portions of the film may be unrolled only a predetermined distance and then temporarily locked until 20 exposure has been made, thus avoiding a forming of blanks and the overlapping of film sections when taking pictures. Further objects will hereinafter appear.

The invention consists of the parts and 25 the construction and combination of parts as hereinafter more fully described and claimed, having reference to the accompanying drawings, in which—

Figure 1 is a side elevation of the camera 30 showing the application of the invention.

Fig. 2 is an enlarged detail rear view of the camera casing partly in section showing the position of the locking pawls.

Fig. 3 is a section on line 3—3 of Fig. 2. 35 Fig. 4 is an enlarged detail view partly in section, of the inner end of the wire operated trip.

Fig. 5 is a similar view of the opposite end of the trip.

40 Referring to the drawings in detail, A indicates the main housing of the camera; 2 the removable back section; 3 the hinged front section; 4 the bellows and 5 the lens, which in this instance is provided with a 45 shutter and an adjustable diaphragm of the usual construction.

Mounted interior of the housing is a winding reel 6 and an unwinding reel 7. Turnably mounted on one of the sections supporting the unwinding reel is a ratchet wheel 8 and pivotally mounted on a stud screw 9 secured in the side of the casing is a locking pawl, in this instance provided with four arm extensions, such as indicated at 55 10—11—12 and 13, respectively.

Also pivotally mounted on the side of the

casing is a second spring actuated pawl 14, which is provided for the purpose of engaging the pawl extension 10 and locking the same together with the remaining connected 60 pawls, in a predetermined position, as will hereinafter be described.

Passing through the camera housing is a flexible tube 15 in which is slidably mounted a trip wire 16. The inner end of this wire 65 is connected to a piston 17 which is slidably mounted in a cylinder 18 and normally held in the position shown in Fig. 4, by means of a spring 19. The opposite end of the wire 16 and the flexible housing 15 is extended 70 to a push button 20 where the housing is secured and the wire 16 is connected to a movable sleeve 21 through means of a plunger 22 and a pin 23. A second flexible housing 24 is also connected to the push button which 75 is provided for the purpose of opening the shutter. The opposite end of this housing is suitably secured to the shutter housing, and a wire 25 passing through the housing 24 is directly connected with the shutter to 80 open same in the usual manner.

Formed in one edge of the film employed is a series of perforations 26. These perforations are so arranged and spaced apart that one perforation will be brought into 85 register with the pawl 13 every time a new film section has been moved into alinement with the lens of the camera. The film will here be temporarily locked until exposure has been made, as the pawl 13 carrying a 90 roller 13^a will drop through the registering film opening and lock same against movement in this manner preventing the film from being turned too far and also overlapping of same when the pictures have been 95 taken.

The pawl shown at 12 is mounted in direct alinement with the ratchet wheel 8 and is provided for the purpose of locking the reel 7 and the ratchet wheel 8 against turning movement when a new film section has been turned into place. The pawl section 10 is mounted in alinement with the secondary pawl 14 and when in engagement with same serves as a means for holding the 100 105 pawls 12 and 13 out of engagement with their respective co-operating parts.

In operation with the film reel 7 inserted and the free end secured to the winding reel 6, it is only necessary to turn the winding reel by means of the key 30 in the direction of the arrow shown until a film perfo-

ration 26 moves into register with the roller and pawl 13. A pin 8^a secured on the outer face of the ratchet wheel 8 will at this point engage the secondary pawl 14 and rock it 5 a sufficient distance to release it with relation to the pawl 10, thereby permitting the pawls 12 and 13 to drop into engagement one with the ratchet wheel and the other with the film perforation. However, should 10 the pin 8^a trip the pawl 14 and release the lever 10 before the film perforation 26 reaches a position opposite pawl 13, as when the diameter of roll 7 decreases with the unwinding of the film, said pawl 13 will 15 drop onto the film by reason of spring 19, and its roller 13^a will ride on the film until the perforation moves therebetween whereupon the pawl 13 will move therein to apply the pawl 12 to the ratchet. Both the un- 20 winding reel and the film is in this manner temporarily locked against movement and the film is in readiness for exposure. This is accomplished by pulling outwardly on the movable sleeve section 21. The wires 16 25 and 25 are in this manner simultaneously pulled in an outward direction thus causing the shutter to be tripped and the respective pawls 10—11—12 and 13 to be moved from the dotted line, or locked position shown, 30 to the full-line released position shown, where pawl 10 is again engaged by pawl 14 and locked to hold the pawls 11—12 and 13 in released position. This position is maintained until a new film section has been 35 turned into position, as the secondary latch 14 will not release the pawls until it is tripped by the pin 8^a. This tripping movement does not take place until a complete new section of film is moved into place and 40 as the pawls are held in raised and locked position during the movement of the new film section into position, it can readily be seen that a double exposure of the film cannot take place because the push-button will 45 be held in depressed position until the latch 14 is tripped and the pawls released. The springs 19 and 20^a will at this time retract the wires 16 and 25 and permit the pistons 17 and 22 to move back to normal position. 50 The pawl 12 therefore moves into engagement with the ratchet wheel 8 while the pawl 13 carrying the roller drops into the film perforation which happens to be in register. Further turning movement of the film 55 beyond a predetermined distance is therefore prevented, and formation of blanks on the film is also prevented, as it is impossible to move a new film section into position until the present film section has been exposed. This can readily be seen when it is 60 realized that the pawls 10—11—12 and 13 will remain in locked position until the push-button is operated and the shutter is opened. 65 The attachment as a whole is simple in

construction and so compact and small that it may be installed or applied to practically any make camera now employed or against the film if the perforation is out of registry.

The unwinding reel should preferably be 70 provided with two or more perforations for the reception of pins 7^a carried by the ratchet wheel, this being preferably as a permanent lock is thereby formed between the unwinding reel and the ratchet wheel 75 as long as the reel remains within the camera.

The materials and finish of the several parts of the camera may otherwise be such as the experience and judgment of the manufacturer may dictate.

Having thus described my invention what I claim and desire to secure by Letters Patent is:

1. A camera including a film-carrying 85 reel, a lock arm to engage the reel and hold it against movement when its film has moved a predetermined distance, a second arm fixedly related to the lock arm, a cylindrical housing adjacent the second arm 90 and formed with a slot, a plunger slidable in the housing and provided with a pair of pins extending outwardly through the housing slot and straddling the second arm to oscillate the same and thereby swing the 95 lock from the reel and means for sliding the plunger.

2. A camera including a film-carrying reel, a lock arm to engage the reel and hold it against movement when its film has 100 moved a predetermined distance, a second arm fixedly related to the lock arm, a cylindrical housing adjacent the second arm and formed with a slot, a plunger slidable in the housing and provided with a pair of pins extending outwardly through the housing slot and straddling the second arm to oscillate the same and thereby swing the lock arm from the reel, means for sliding the plunger in one direction, a coiled spring 110 within the housing for pressing the plunger in the opposite direction, a third arm rigid with the aforesaid arms, a pawl engageable with the third arm when the second arm is operated by said means to hold said third arm against the tension of the coiled spring, 115 and means operable by the reel to release the third arm from the pawl.

3. A camera including a film-carrying reel having a ratchet and a trip, a pawl co-operating with the ratchet to lock the reel against movement when its film has moved a predetermined distance, an arm fixedly related to the pawl, a second pawl engageable with the arm for holding the first pawl inoperative, said second pawl being rendered inoperative by the trip to release the arm and first pawl, a second arm also rigidly related to the first pawl and arm for moving the latter into engagement with said second 125 130

pawl, and means for operating the second arm.

4. A camera including a film-carrying reel having a ratchet and a trip, a pawl coöperating with the ratchet to lock the reel against movement when its film has moved a predetermined distance, an arm fixedly related to the pawl, a second pawl engageable with the arm for holding the first pawl inoperative, said second pawl being rendered inoperative by the trip to release the arm and first pawl, a second arm also rigidly related to the first pawl and arm for moving the latter into engagement with said second pawl; a third pawl fixedly related to the first pawl and normally held spaced from

the film by the engagement of the second pawl with the first arm and adapted when released to ride on the film until a perforation in the latter registers therewith and 20 then to pass into the perforation for effecting engagement of the first pawl with the ratchet, and means for operating the second arm.

In witness whereof I have hereunto set 25 my hand in the presence of two subscribing witnesses.

GERARD J. TERWIEL.
